UNITED STATES PATENT OFFICE.

EDWARD GEORGE RIVERS, OF RICHMOND, ENGLAND.

ELECTRICAL HEATING ELEMENT OR RESISTANCE.

No. 851,440.

Specification of Letters Patent.

Patented April 23, 1907.

Application filed June 11, 1906. Serial No. 321,218.

To all whom it may concern:

Be it known that I, EDWARD GEORGE RIVERS, a subject of the King of Great Britain, residing at Beverley Lodge, Richmond, in the county of Surrey, England, have invented certain new and useful improvements in Electrical Heating Elements or Resistances, of which the following is a specification.

This invention relates to an electrical 10 heating plate which can also be used as a resistance, and the object thereof is to construct the plate in such a manner as to secure perfect insulation of the conductor coupled with the exhibition of heat due to 15 resistance and, furthermore, to so imbed a metallic contact as to preserve the metal from oxidation and consequently obtain perfect electrical conductivity.

With the foregoing and other objects in 20 view the invention consists of the novel construction of electrical heating plate as hereinafter set forth and illustrated in the accompanying drawings, wherein is shown the preferred embodiment of the invention, but it is 25 to be understood that changes, variations, and modifications can be resorted to which come within the scope of the claims hereunto appended.

In describing the invention in detail, reference is had to the accompanying drawings, 30 wherein like reference characters denote corresponding parts throughout the several views, and in which

Figure 1 is a plan of an electrical heating plate in accordance with this invention, and 35 Fig. 2 is a longitudinal sectional view thereof.

Referring to the drawings by reference characters, *a* denotes a plate formed from baked clay of any convenient size or shape, 40 preferably rectangular in contour, and which has one face thereof formed with a depression or groove *b* which starts at one corner of the plate, passing backward and forward over the surface of the plate, and terminating at 45 the furthest opposite corner arranged diagonally with respect to that corner from which the groove started. The groove *b* is so disposed throughout the face of the plate as to form a plurality of ridges *c* of a width equal 50 to the width of the groove. The ridges are so disposed throughout the face of the plate as to not interrupt the groove *b* or, in other words, so that the groove will be continuous from one corner to the opposite diagonal corner of the plate. By way of example, it will 55 be stated that, on a plate six inches square,

the groove has a run of five feet, for 100 and 200 volts, but, for voltages lower than 100, the groove is correspondingly varied in length and depth. The groove is filled with a paste 60 of silicated carbon formed from soluble silica (either K_2OSiO_2 or Na_2OSiO_2 or other convenient formula for soluble silica) diluted with water in convenient proportions. By way of example, say one part of silica to two 65 parts of water, mixed in the proportions of one of the foregoing to two of carbon powder. The paste is dried and subsequently heated to 250° Faht.

The electrical contacts are indicated by 70 the reference character *d* and are situated at the opposite diagonal corners of the plate, but this arrangement may be varied to bring both of the contacts to the same side. Each of the contacts consists of a small metallic 75 screw bolt *e* inserted through an opening at each end of the carbon run on the plate, and on the carbon side a metallic washer *f* is placed under the bolt head. Positioned under the washer *f* is a short length of flexible 80 stranded, or solid wire *g*, the latter being twisted with one turn, and the two ends of the wire are brought over the commencement of the groove *b*. A blob of carbon paste *h* is then placed upon the plate *a*, under the ends 85 of the wire, and the latter when pressed down, are covered with a further blob of paste, so that the terminal wires are completely imbedded and protected from oxidization. The bolt is then secured by a back nut and washer. 90 The whole is then dried and heated as before.

It is to be understood that the paste is carried by its own adhesion to the plate and the two combined form the element. A number 95 of these plates may be assembled and wired in parallel or in series to form a heater. In special cases I use an insulating and heat-resisting material such as "uralite" instead of baked or kilned clay to carry the carbon paste.

What I claim is:

1. A plate for the purpose set forth comprising a body portion of clay having one face provided with a groove extending from a corner at one end of the body portion to a corner 105 at the opposite end thereof and having parts of its length arranged in parallelism with respect to each other, thereby providing said face of the body portion with ridges alternately disposed with respect to each other 110 and of a width substantially equal to the width of the groove, and a resistance mate-

- rial formed from a paste of silicated carbon within said groove and capable of attaching itself when heated to the base by its own adhesion.
5. 2. A plate for the purpose set forth comprising a body portion of clay having one face provided with a groove extending from a corner at one end of the body portion to a corner at the opposite end thereof and having 10 parts of its length arranged in parallelism with respect to each other, thereby providing said face of the body portion with ridges alternately disposed with respect to each other and of a width substantially equal to the 15 width of the groove, a resistance material formed from a paste of silicated carbon within said groove, capable of attaching itself when heated directly to the clay base by its own adhesion, and contacts imbedded in said 20 body portion.
3. A plate for the purpose set forth consisting of a body portion of clay having one face thereof provided with a resistance material formed from a silicated carbon insert extending from one corner of the body portion to the opposite corner thereof and having parts thereof arranged in parallelism with respect to each other thereby providing the 25 said face of the body portion with alternately disposed ridges of a width equal to the width of the carbon insert, said insert capable of attaching itself when heated directly to the 30 clay base by its own adhesion.
4. A plate for the purpose set forth consisting of a body portion formed from baked 35 clay and provided with a resistance material formed from a silicated carbon insert in one
- face thereof, said insert extending from one corner of the body portion to a corner arranged diagonally with respect to the other corner, said insert so disposed throughout the 40 face of the plate as to provide said face with a plurality of ridges of a width substantially equal to the width of the body portion, said ridges extending in parallelism with respect to each other, and said insert capable of attaching itself when heated directly to the clay base by its own adhesion.
5. A plate for the purpose set forth consisting of a body portion formed from baked 45 clay and provided with a resistance material formed from a silicated carbon insert in one face thereof, said insert extending from one corner of the body portion to a corner arranged diagonally with respect to the other 50 corner, said insert so disposed throughout the face of the plate as to provide said face with a plurality of ridges of a width substantially equal to the width of the body portion, said ridges extending in parallelism with respect to each other, said insert capable of attaching itself when heated directly to the 55 clay base by its own adhesion and contacts connected to the body portion and embodying conducting wires having the ends thereof 60 embedded in a silicated carbon.

In testimony whereof I have hereunto set my hand in presence of two subscribing witnesses.

EDWARD GEORGE RIVERS.
